UNITED STATES PATENT OFFICE.

JOHN G. SMITH, OF JACKSON, TENNESSEE.

SHIP PROTECTOR.

Application filed July 18, 1921. Serial No. 485,514.

To all whom it may concern:

Be it known that I, JOHN G. SMITH, a citizen of the United States, residing at Jackson, in the county of Madison and State of Tennessee, have invented certain new and useful Improvements in Ship Protectors, of which the following is a specification.

This invention relates to ships, and the primary object of the invention is to provide an improved protecting device therefor, so as to effectively prevent injury to the hull of the ship by shells, mines, or by collision.

Another object of the invention is the provision of expansible guard members carried by the sides and bow of the ship having an improved means for moving the same to an extended position in relation to the hull of the ship, so as to protect the hull from shock, said means for moving the plates to their extended position also forming shock absorbers, and means for returning the protection members to their contracted or inoperative positions in abutting relation to the sides of the ship, so as to facilitate the movement of the ship when docking or the like.

Another object of the invention is to provide an improved armor for the hulls of ships embodying novel movable protecting plates, the plates being connected with the hull of the ship by pneumatic shock absorbers, which effectively prevent the transmission of shock to the hull of the ship set up by any cause.

A still further object of the invention is to provide an improved means for protecting ships of the above character, which is durable and efficient in use, one that is simple and easy to manufacture, and one which can be incorporated with ships at a minimum cost.

With these and other objects in view, the invention consists in the novel construction, arrangement and formation of parts as will be hereinafter more specifically described, claimed and illustrated in the accompanying drawings, forming a part of this specification, in which drawings:

Figure 1 is a diagrammatic view of the improved protecting device incorporated with a hull of a ship, the ship hull being shown in section.

Figure 2 is an enlarged detail view through one of the shock absorbing and operating cylinders for the bow and protecting device, taken on the line 2-2 of Figure 1.

Figure 3 is a fragmentary detail horizontal section, taken on the line 3-3 of Figure 2, illustrating the means of operatively connecting the side plates of the bow protecting device together. 60

Figure 4 is an enlarged fragmentary vertical transverse section through a portion of the side of the ship, taken on the line 4-4 of Figure 1.

Figure 5 is a detail longitudinal section 65 taken on the line 5-5 of Figure 6, illustrating the means of mounting the bow armor on the actuating pistons.

Figure 6 is a detail vertical section taken on the line 6-6 of Figure 5. 70

Figure 7 is a detail section taken on the line 7-7 of Figure 2, illustrating the means for connecting the cylinders to the armor of the ship.

Figure 8 is an enlarged detail view, partly 75 in section, of one of the valves utilized for controlling the air to the operating and shock absorbing cylinders.

Figure 9 is a plan view of the same.

Figure 10 is a detail section through the 80 valve, taken on the line 10-10 of Figure 8.

Figure 11 is a longitudinal section through the operating handle therefor.

Figure 12 is a fragmentary longitudinal section taken through the relief valve carried by each of the cylinders. 85

Referring to the drawings in detail, wherein similar reference characters designate corresponding parts throughout the several views, the letter A indicates the 90 ship; and B, the improved protecting device therefor.

The ship A has been merely shown for the purpose of illustrating the improved invention, and may be of any preferred size 95 or type. As shown, the ship A includes the sides 10, the bow 11, and the stern 12. The improved protecting device B includes the side protecting device C, the bow protecting device D, and the means E and F for controlling the movements of the protecting devices B and C and for absorbing shock transmitted to these devices. 100

The means C for protecting the sides of the ship includes the longitudinally extending side plates 15 and 16, which can be made of steel armor plate if so desired. I do not desire, however, to limit myself to forming the plates of solid steel, as it can be readily seen that the same can be formed 110

of steel netting, lattice work or the like. The side plates 15 and 16 extend the entire length of the sides of the ship, and the rear ends thereof are curved inwardly as at 17 5 to provide a protection for the stern of the ship, as can be readily seen by referring to Figure 1 of the drawings.

The protecting device D for the bow of the ship includes side plates 18 and 19, which are curved to conform to the configuration of the bow of the ship, which it is associated with. The rear terminals of the plates 18 and 19, overlie the plates 15 and 16, so that during the expansion or the 15 extending of these plates to their operative positions, the same will not pass each other, and thus leave a portion of the hull exposed. These plates 18 and 19 have their forward terminals provided with hinged barrels 20 which receive a suitable pivot rod 21. Thus it can be seen that these plates 18 and 19 can be swung on the pivot rod 21 toward and away from the opposite portions of the ship.

25 The means E and F for moving the protecting devices C and D to their operative and inoperative positions and for absorbing shock are constructed identically the same, and each includes a plurality of pneumatic cylinders 25 and 30. As shown, the cylinders 25 are arranged along the sides 10 of the ship, while the cylinders 30 are arranged along the bow of the ship, and if so desired a series of superposed rows of 30 these cylinders may be provided, so that the plates can be projected equi-distantly from the sides of the ship and all points thereof. Each of the cylinders 25 and 30 have slidably mounted therein, pistons 26, which 35 carry the outwardly extending piston rods 27. The piston rods 27 for the plates 15 and 16 of the protecting device C for the sides of the ship are provided with enlarged heads 28, which are riveted or otherwise secured to the plates as at 29. The 40 outer ends of the piston rods 27, which are positioned directly at the forward portion of the ship, are provided with eyes 29', which are extended around the pivot rods 21. The eyes 29' as shown, are disposed intermediate the hinged barrels 20 formed 45 on the plates 18 and 19 of the bow protecting device.

50 The cylinders 25 and 30 can be held in place by suitable brackets 26' as shown in Figure 4 of the drawings and the inner ends thereof can be provided with flanges 25' which can be riveted or otherwise secured as at 29' to the hull of the ship. The 55 piston rods 27 extend through stuffing boxes 28' carried by the sides of the ship which prevent the seeping of water into the hull of the ship. Each of the piston rods 27 of the cylinders 25 and 30 are provided with 60 a rebound springs 27', which engage suitable

collars formed on the rods and against the stuffing boxes 28'. As shown, these springs tend to normally urge the pistons inwardly.

Now the pistons 27 for the bow protecting device D are located on the opposite 70 sides of the pistons arranged directly at the front portion of the ship, and are also provided with eyes 31. These eyes 31 are mounted for swinging movement on pivot pins 32, which are carried by brackets 33. 75 These brackets 33 are secured to the inner faces of the carriages 34, which are mounted for sliding movement longitudinally of the ship in tracks 35, which are secured to the inner faces of the side plates 18 and 19 of 80 the bow protecting device D. The carriages 34 are provided at their upper and lower edges with anti-friction wheels 36, for engaging the track, and at their inner edges with anti-friction wheels 37 which are adapted 85 to engage the inner faces of the track. As shown the tracks 35 are of substantially channel beam construction.

It is obvious that when the device is moved to its extended operative position, the 90 plates 18 and 19 of the bow protecting device are allowed to slip forwardly, owing to the means of mounting the plates on the carriages as just described. This means forms an important part of my invention, as it 95 can be seen that it permits the easy moving of the plates to their extended operative position, or to their contracted inoperative positions, with a minimum amount of effort.

The pistons in the cylinders E and F are 100 adapted to be moved back and forth by a suitable fluid, such as compressed air, steam or the like, and as shown in the drawings, an air compressor 50 is provided. This compressor 50 is connected by means of a line 105 pipe 51 to a suitable storage tank 52. The compressor 50 and the storage tank 52 can be located at any preferred point on the ship. In order to control the flow of the fluid through the cylinders, a valve 55 is provided. A valve 56 is also provided for controlling the exhaust from the cylinders, and the valves 55 and 56 are constructed identically the same. As shown, each of these 110 valves 55 and 56 include a dome-shaped body 57, which is secured to a suitable base 58 which has arranged therein a valve plate or seat 59. This valve plate or seat 59 is engaged by a rotary valve plate 60, which is provided with a valve stem 61. The valve 115 stem 61 has the terminals rotatably mounted respectively in the dome 57 and the base 58, and upon movement of the valve stem, the valve plate 60 will be moved therewith. The upper end of the valve stem 61 is provided 120 with a polygonal portion, which is adapted to fit in the polygonal portion 62 of the operating handle 63. This operating handle 63 is provided with a suitable pivotal dog 64 which is adapted to engage in indentations 125 130

65 formed in the upper portion of the dome, which hold the valve stem and valve plate 60 against movement. The valve plate 60 is provided with a single opening 67, which is 5 adapted to be moved into registration with any one of a plurality of openings 68 formed in the plate 59. These openings 68 formed in the plate 59 have communicating therewith pipes, which will be hereinafter more 10 fully described. The dome 57 of the valve 55 has communicating therewith a lead pipe 69, which extends from the storage tank. The dome 57 of the valve 56 has communicating therewith a pipe, which leads to the 15 atmosphere.

As shown, each of the plates 59 are provided with four openings 68, and these openings of the valve 55 are designated respectively by the reference characters 1^R, 2^R, 20 1^L and 2^L. The plate 59 of the valve 56 has these openings designated respectively by the reference characters 3^R, 4^R, 3^L and 4^L. The openings 1^R, 2^R, 1^L and 2^L have communicating therewith respectively line 25 pipes 70, 71, 72 and 73. The pipes 70 and 71 control the expansion and contracting of the side protecting devices C and have communicating therewith branch pipes 74, and 75, which lead respectively to the rear and 30 front portions of the cylinders 25. The pipes 72 and 73 control the expansion and contraction of the bow protecting device D and have branch pipes 76 and 77 communicating respectively therewith, which lead 35 respectively to the rear and front portions of the cylinders.

As stated, the valve 56 controls the exhaust from the cylinders and the openings 3^R and 4^R have communicating therewith 40 line pipes 78 and 79, which control the exhaust from the cylinders 25 of the side protecting device C. The pipes 78 and 79 have communicating therewith the branch pipes 80 and 81, which lead respectively to the forward and rear ends of the cylinders 25. The openings 3^L and 4^L have communicating therewith pipes 82 and 83, and control 45 exhaust from the bow protecting cylinders 30. These pipes 82 and 83 have communicating therewith a plurality of branch pipes 84 and 85, which lead respectively to the rear and forward portions of the cylinders 30. If so desired, the pipes 70, 71, 72 and 73 leading from the valve 55 may be 50 provided with check valves 86, in order to hold the pressure within the dome 57 of this valve.

In operation of the improved protecting devices C and D, when it is desired to move 55 the plates 15 and 16 of the side protecting devices, and the plates 18 and 19 of the valve protecting device D to extended operative position as shown by dotted lines in Figure 1 of the drawings, the handle 63 of the valve 55 is first operated, so as to align

the openings 67 in the valve plate 60 with the opening 1^R which will permit the flow of fluid from the dome of the valve through the pipe 70 to the branch pipes 74 to the rear end of the cylinders 25. This will force 70 the pistons 26 to the forward ends of the cylinders, thus moving the plates 15 and 16 to their extended operative position. The handle 63 of the valve 55 is then moved to align the opening 2^L which will permit the 75 flow of the fluid to the pipe 72, the branch pipes 76, to the rear ends of the cylinders 30 of the bow protecting device D, which will force the pistons in these cylinders to their extended position, and the plates 18 and 19 80 to their extended positions. This movement of the pistons forces the plates 18 and 19 forwardly and outwardly, which movement is permitted by the hinging of the plates 18 and 19 and their connection with the 85 piston rods 26 as heretofore described.

When it is desired to move the protecting devices C and D, to their inoperative positions adjacent to the sides of the ship, the handle 63 of the valve 56 is operated, 90 so as to move the opening 67 in the valve plate 60 of this valve in alignment with the opening 3^L, which will establish atmospherical communication to the branch pipes 84, which communicate with the rear end 95 of the cylinders 30 of the bow protecting device D and the lead pipe 82, thus permitting the escape of pressure from the rear ends of these cylinders. The handle 63 of the valve 55 is then operated, so as to align 100 the openings 67 in the valve plates 60 of this valve, with the opening 1^L, which will permit fluid to flow through the branch pipes 77 to the forward ends of the cylinders 30, which will force the pistons 26 105 rearwardly and thus move the bow protecting device D inwardly. The handle 63 of the valve 56 is then operated to move the opening 67 into registration with the openings 3^R which permits the establishing of 110 atmospherical communication with the rear ends of the cylinders 25 through the branch pipes 81 and the main pipe 79. The handle 63 of the valve 55 is then moved so as to align its opening 67 with the openings 2^R 115 which permit the flow of fluid to the main pipe 71 and the branch pipes 75 and the fluid entering the forward end of the cylinder 25 will force the pistons rearwardly, thus moving the plates 15 and 16 of the 120 side protecting device C to their inner positions.

When the protecting devices C and D have been forcibly returned to their inoperative position by pressure and it is desired to 125 again extend the same, the pressure from the forward ends of the cylinders 25 and 30 is released by the operation of the valve 56 and air introduced to the rear end of the cylinders 25 and 30 by the actuation of the 130

valve 55, which will again move the plates C and D to their forward extended positions. Pressure is released from the rear ends of the cylinders 25 and 30 by the actuation 5 of the handle 63 of the valve 56, and it can be seen that the handle 63 is first operated so as to align the opening 67 of the valve plate 60 of the valve 56 with the opening 4^R, which will establish atmospherical communication with the forward ends of the cylinders 25 through the branch pipes 80 and the main pipe 78. The valve handle 63 of the valve 55 is then operated, so as to align the openings 67 of the valve 55 with the opening 1^R which will permit the flow of fluid through the main pipe 70 and the branch pipes 74 to the rear ends of the cylinders 25 which will force the pistons forwardly and the plates 15 and 16 to their 10 extended operative positions. The valve handle 63 of the valve 56 is then operated, so as to align the openings 67 with the opening 4^L, which will establish atmospherical communication with the forward ends of the cylinders 30 through the branch pipes 85 and the main pipe 83. The valve handle 63 of the valve 55 is then operated, so as to align the opening 67 with the opening 2^L, which will permit the flow of fluid to the 15 line pipe 72 and the branch pipe 76 to the rear ends of the cylinders 30, thus moving the pistons outwardly and the plates 18 and 19, forwardly and outwardly.

A safety valve 90 is provided for each of 20 the cylinders 25 and 30, and this safety valve is connected to the rear ends thereof. As shown, the safety valve 90 includes a cylindrical casing 91, the forward end of which is provided with a nipple 92, which is 25 threaded into the rear end of the cylinders as heretobefore stated. Each of the cylindrical casings 91 has reciprocably mounted therein a piston 93, which is normally forced toward the forward end of the casing 91 by 30 means of an expansion spring 94, which is coiled around the piston rod 95 of the piston 93. If so desired, the piston rod 95 may have its outer end provided with suitable graduations 96 and extended through a 35 hollow screw 97, which can be utilized for adjusting the tension of the spring 95, in order to control the movement of the piston 93. The cylindrical casing 91 intermediate its ends is provided with air escape openings 98, and it can be seen that when the piston 93 is moved beyond the openings 98 through excess pressure, the air is permitted to escape from the rear ends of the cylinders 25 and 30. These release or check 40 valves are provided so that if the plates are struck by a shell or other obstruction, the air will be permitted to escape when the same is compressed to a certain pressure, in order to prevent the breaking of the cylinders. 45 The too forcible return of the plates after the

plates have been forced inwardly by a shell or the like, is prevented by the rebound spring 27.

From the foregoing description, it can be seen that an improved and novel means has 50 been provided for effectively protecting a ship from striking obstructions and the like.

Changes in details may be made without departing from the spirit or scope of this 55 invention; but,

I claim:

1. The combination with a ship's hull, of a protecting device therefor comprising side plates disposed on opposite sides of the hull 60 and terminating short of the bow of the ship, rearwardly curved extensions formed on the rear edges of the side plates for protecting the stern of the ship, a pair of front plates for protecting the bow of the ship, 65 means pivotally securing the forward edges of the last mentioned plates together, means carried by the hull and engaging said pivot means for moving the last mentioned pair of plates outwardly of the bow, means for 70 swinging the last mentioned plates on said pivot means, and means carried by the ship for moving the side plates toward or away from the sides of the ship.

2. A ship protecting device, the combination with a ship hull, of a protecting device for the sides of the hull and for the bow of the hull including movable plates arranged for movement toward and away 75 from the sides of the hull, a plurality of cylinders secured to the hull and extending longitudinally thereof, pistons and piston rods reciprocably mounted in the cylinders, means for controlling the flow of compressed air to each end of the cylinders, means for 80 controlling the exhaust of air from each end of the cylinders, and expansion springs coiled about said piston rods for preventing rebound of said plates when said plates have 85 been forcibly moved inwardly and for normally holding the plates to their inner normal positions.

3. The combination with a ship hull, of a protecting device including protecting plates for the opposite sides of the hull 90 and protecting plates for the bow of the hull, means pivotally connecting the plates for the bow of the hull together for swinging movement, a plurality of cylinders secured to the inner surface of the hull, pistons and 95 piston rods reciprocably mounted in the cylinders, means rigidly securing the piston rods of certain cylinders to the plates for the sides of the hull, means slidably and pivotally connecting certain of the piston rods to the plates for the bow of the hull, and means connecting certain other of the piston rods to the pivot means for connecting the plates for the bow of the hull together.

4. The combination with a ship hull and a protecting device for the bow thereof including a pair of plates shaped to conform to the configuration thereof, a pivot pin pivotally connecting the forward ends of the plates together, tracks secured to the inner surface of said plates, a plurality of cylinders carried by the inner surface of the hull, pistons and piston rods reciprocally mounted 10 in the cylinders, carriages carried by certain of the piston rods and slidably mounted in said tracks, and means pivotally connecting certain other of the piston rods to the pivot pin utilized for connecting the 15 plates together.
5. The combination with a ship hull, of a protecting device for the bow thereof including a pair of plates curved to conform to the configuration of the hull, hinged barrels, formed on the forward edges of the 20 plates, a hinge rod connecting the hinged barrels together, longitudinally extending tracks carried by the inner surface of the plates, carriages slidably mounted in said tracks, a plurality of longitudinally extending 25 cylinders carried by the inner surface of the hull, piston and piston rods slidably mounted in said cylinders, means pivotally connecting certain of the piston rods to said 30 carriages, means pivotally connecting other of said rods to the hinge rod, and adjustable

relief valves carried by the rear ends of said cylinders.

6. The combination with a ship hull, of movable plates for the sides of the hull and 35 movable plates for the bow of the hull, means pivotally connecting the plates for the bow of the hull together, the plates for the sides of the hull and for the bow of the hull being arranged in overlapped relation, 40 a plurality of longitudinally extending cylinders secured to the inner face of the hull, pistons and piston rods reciprocally mounted in said cylinders, means operatively connecting the outer ends of the piston rods to said plates, supply pipes for the cylinders for the plates for the bow of the hull, branch pipes connecting the supply pipes to opposite ends of said cylinders, a valve for controlling the flow of fluid 45 through the supply pipes to the opposite ends of the cylinders for the plates for the sides of the ship and the cylinders for the plates for the bow of the ship, exhaust pipes for the cylinders of the bow plates and 50 for the plates for the sides of the hull, branch pipes connecting the exhaust pipes to the opposite ends of all of the cylinders, and a separate valve construction for controlling the exhaust through said pipes.

JOHN G. SMITH.
